(57) **CLAIM**

The ornamental design for a water bottle filter, as shown and described.

DESCRIPTION

FIG. 1 is a top perspective view of a water bottle filter showing my new design;

FIG. 2 is a front elevational view thereof, the rear elevational view, right side elevational view and left side elevational view being identical thereto;

FIG. 3 is a top plan view thereof; and,

FIG. 4 is a bottom plan view thereof.

The broken lines shown in FIGS. 1 and 3-4 form no part of the claimed design.
